Primary Examiner — Philip S Hyder

(57) **CLAIM**

The ornamental design for a plier handle, as shown and described.

DESCRIPTION

1.Plier handle

1.1 : Top

1.2 : Perspective

1.3 : Right

1.4 : Left

1.5 : Back

1.6 : Front

1.7 : Bottom

1.8 : Detailed view

The design comprises a handle for a pair of pliers; no protection is claimed for the logo shown in reproduction 1.8. The broken lines are included for the purpose of showing portions of the plier handle that form no part of the claimed design.

1 Claim, 8 Drawing Sheets
